STAMP HOLDER

Charles A. Swanson, Chicago, Ill.

Application March 16, 1934, Serial No. 715,855

5 Claims. (Cl. 129—20)

This invention relates to a holder for stamps or like articles. It comprises a cover member of convenient size such as can be inserted into an ordinary desk drawer or readily carried upon the person, and card members therein in book form having clips for detachably carrying stamps either in sheets or individually and in sorted and readily detachable arrangement. An elastic member is associated with each card for further detachably securing the stamps or like articles in position upon the card.

It is an object of this invention to provide a compact and inexpensive holder for stamps or like articles, which is durable and convenient, and in which the stamps and the like are readily accessible for use.

It is a further object to provide a neat and compact holder which can be readily carried upon the person or inserted in an ordinary desk drawer, but yet which has sufficient capacity to carry readily a considerable quantity of stamps or like articles of various denominations and size, such as may be required by the user.

It is a further object to provide a holder for stamps and the like in which the stamps or like articles may be readily inserted into position, the stamps being retained thereafter in sorted and protected condition.

A still further object is to provide a holder in which stamps or like articles may be easily found according to denomination and may be readily removed, and to provide a holder in which the absence or shortage of any particular denomination of stamp or class of like article may be readily ascertained.

The preferred embodiment of my invention is illustrated in the accompanying drawing in which:

Figure 1 is a perspective view of my stamp holder, the cover being opened to show a number of stamp carrying cards and the stamp carrying means mounted thereon, one card being raised.

Figure 2 is a perspective view of a sheet of stamps or like articles preferably perforated and gummed, showing the preferred method of folding the sheet prior to insertion into the holder.

Figure 3 is a plan view of a stamp carrying card.

Figure 4 is a sectional view of a part of my holder taken on the line 4—4 of Figure 1, showing six stamp cards lying flat.

Similar reference characters will be used throughout the specification to indicate corresponding parts upon the drawing.

A cover member 10 comprising two flat portions 11 and 12, adapted to be folded upon each other at 13, forms the outer covering member for my stamp holder. A backing member 16 overlies the inner side of the portion 12 of the cover and the edges of the covering material for the portion 12 are folded over upon the backing member at both ends and along one side thereof at 14 and 15, respectively, thereby securing to the cover portion 12 the backing member 16. As will be seen more particularly in Fig. 4 no means is provided for securing the left-hand longitudinal edge of the backing member to the cover. A suitable pocket is thus formed between the backing member of the portion 12 of the cover into which loose stamps or like articles may be readily inserted and from which they may be readily removed. The pocket which is in a sense a part of the cover is not readily noticeable and thus constitutes a secret or concealed container for stamp money, stamp memoranda and the like.

The plurality of cards 17 are mounted within the cover member in book form, as will be seen more particularly in Fig. 1. The cards carry two sets of aligned perforations 18 and the backing member 16 carries two corresponding perforations 19. A cord member 20, suitably tied at 21, is threaded through the perforations in the backing member and cards, to detachably secure the cards together and upon the backing member in book form within the outer cover member. It will be seen that the cord may be readily untied to allow for the addition or removal of the cards. The tension of the cord member may be adjusted in the tying operation so that just sufficient slack is left therein to allow the cards to be overturned, after the manner of the leaves of a book, as is shown in Fig. 1. Metal rings 22 are provided to reinforce the edges of the perforations 19 in the backing member. Although no corresponding metal members are shown on the cards, it will be readily apparent that they could be provided therein to reinforce the edges of the perforations 18.

Each card 17 carries at its upper end a plurality of spring clips 23 for detachably securing sheets of stamps or the like or individual stamps upon the card members. The clips are preferably mounted upon both sides of the card at the top thereof, and in the specific embodiment shown in the drawing there are three clips upon each side at the top of the card. The provision of clips upon both sides of the card increases the capacity of the holder, with respect to the number of stamp holding cards provided. The

clips are secured to the cards by any suitable means or they may be formed from the cards themselves by appropriately slitting and flexing the card material near the top. In the embodiment illustrated separate metallic clips are secured to the cards by metal rivets 24 of suitable form. Each rivet engages two clips, one on each side of the card, and secures their ends in position upon the card. Two rivets secure two clips 10 in position, one clip being on each side of the card. By engaging each rivet with two clips a rugged construction is produced, as metal to metal contact is provided at each end of the rivet and strain is relieved from the card itself, 15 which is preferably of card board or like material of less tensile strength than metal.

The clips may be of any desired configuration, and they are adapted to hold the stamps or like articles in position upon the card, as will be seen 20 more particularly in Fig. 3. They are resilient so that the stamps 25 will be held in position, and yet they are sufficiently flexible so that they may be lifted for the ready insertion of the stamps thereunder.

25 The stamp sheets are preferably folded in the manner shown in Fig. 2, prior to their insertion beneath the clips. It has been found in practice that two standard sheets of stamps, embodying 200 stamps in all, may be readily inserted beneath the clips and effectively retained in position.

30 The cards are notched at each edge, as shown at 26, and one or more elastics 27 are provided upon the cards and engage opposed notches for further securing the sheets of stamps in position. The elastics may be adjusted along the length of the cards by shifting them from one pair of notches to another pair. It will be seen that each elastic embraces the entire card and 40 thus may aid in securing the stamps upon both sides of the card in position.

35 The stamps may be readily detached from the ends of the strips either singly or in greater number. If the entire block 28 (Fig. 3) of stamps at the extreme end of the sheet is removed it will be appreciated that with ordinary sheets of stamps ten stamps will be obtained. If more are needed additional stamps may be removed from any sheet which may be provided 50 beneath, or additional stamps may be removed from the adjacent block 29 in any desired quantity. The removal of two blocks of sheets gives twenty stamps. In Fig. 3, three sheets of stamps designated at 30, 31 and 32, are provided, more stamps having been removed from sheets 31 and 32 than from sheet 30. It will be seen that by 55 counting the number of blocks of stamps present in any sheet, and that by further counting the number of individual stamps present in the extreme end block when a more accurate determination is required, a ready inventory may be taken of the number of stamps present in any strip.

60 Stamps are preferably arranged with various denominations on the various cards. By my individual clip retaining means an accurate check can be made at any time upon the number of stamps of any given denomination or classification on hand. While in Fig. 3 I have shown 65 all sheets of stamps secured in position upon the cards it will be appreciated that individual stamps may be secured in position under the clips as well.

70 It will thus be seen that by my stamp holder 75 I provide a construction which will hold stamps

in protected and a classified arrangement, and into which stamps may be readily inserted and from which they may be readily removed. By their arrangement upon the cards in book form a rapid and accurate inventory may be taken of 5 the number of stamps of any particular classification or denomination, thus avoiding annoyance due to the running out of stamps of a particular kind. The stamp carrying cards may be increased in number as may be desired by means 10 of adjustment of the cord member 20.

The entire construction is durable and rugged and yet when the cover member is closed over the cards the complete holder assumes the form 15 of a book, which may be readily and conveniently carried upon the person or inserted within any suitable small container.

It will be apparent that many changes and variations may be made in the preferred form 20 of my holder, which I have specifically described, without departing from the spirit of my invention. I therefore do not desire to be limited to the precise embodiment which I have shown and described, but only as indicated in the following claims.

I claim:

1. A stamp holder comprising a plurality of 30 cards, a backing member, adjustable length means to detachably secure the cards together in book form upon the backing member, a cover 35 for the cards and backing member, a pocket formed between said cover and said backing member, and clips on the cards adapted to detachably secure variable thickness sheets of stamps thereon. 35

2. A stamp holder comprising a cover member, a backing member, means to secure the backing member to the cover so as to form a pocket therebetween, a plurality of cards, aligned perforations in the cards and backing member, a cord passing through said perforations for detachably securing the cards in book form in position upon the backing member, clips on both sides of the cards adapted to detachably secure stamps on the cards, and elastics embracing the 45 cards to further secure the stamps in position thereon. 45

3. In a holder device, a cover member, a backing member, means for securing portions of the backing member to the cover member while leaving other portions of the backing member free to form a pocket between the cover member and the backing member, a plurality of cards, clip means on said cards for detachably securing objects thereto, said cards and backing member 50 having aligned perforations passing therethrough, and a flexible cord passing through said aligned perforations and secured at its ends whereby to secure the cards upon the backing member. 55

4. In a holder device, a cover comprising two 60 flat portions and a center portion flexibly joining the flat portions, a backing member joined to one flat portion along the three edges thereof away from the center portion to form a pocket opening toward the center portion, a plurality of 65 cards removably secured to the unsecured edge of the backing member at points on an edge of and spaced from the ends of the cards, and means extending between the fastened edge of each card and the opposite edge between the 70 points of fastening and an end of the card and adapted to engage and hold objects on the card. 75

5. In a holder device, a cover comprising a flexible foldable medial portion and flap portions 75

on opposite sides of said medial portion, a backing member on one of said flap portions and forming therewith a pocket opening toward the medial portion, a plurality of cards removably secured on said backing member, and clips on said cards adjacent certain edges thereof and adapted to

engage sheet-like objects and secure the same removably on the cards, opposed edges of said cards having registering notches for receiving cord-like holding means thereon to additionally secure the sheet-like objects on the cards.

5

CHARLES A. SWANSON.
